UNITED STATES PATENT OFFICE

2,686,861

ELECTRICAL PAINT REMOVER

George Alfred Waller, Mount Vernon, N. Y.

Application February 17, 1951, Serial No. 211,533

1 Claim. (Cl. 219—21)

1
This invention pertains to electrical heating appliances. More particularly the invention relates to devices of that character designed and adapted for satisfactory and efficient employment in the softening of paint on a painted surface so that it may be easily and readily scraped off or otherwise removed.

Heretofore, in the design of such devices it has been customary to expose the painted surface being treated to the direct action of the electrically heated element carried by the device, the said heated element being so positioned when the device is in use that it is relatively close to said surface. Experience has shown that there are practical objections to an arrangement where the exposed heating element is in approximate contact with the surface being treated among which is the danger of foreign matter from the work accumulating upon the exposed surfaces of the heating element and interfering with the proper functioning of the device. Also, it has been found, as in the case of using a blow-torch, that the close application of intense heat tends to fire certain ingredients in the paint or other surface coating to be removed, with the resulting firing or scorching of the wood and a blistering of the paint surface, leaving a more or less hardened surface due to the charred substance thereon making removal difficult and uncertain. It is desirable to so apply the heat so as to produce the greatest effect at just the point where the required separation is to take place, namely, between the inner surface of the paint surface and the wood face.

To accomplish this desirable result, it is necessary to employ a heating means, the effects from which will penetrate through the paint layer and produce their maximum heating action at the inner surface thereof.

To the attainment of this advantageous and desirable end, the improved and novel heater, incorporating the present invention, is so designed and constructed that it will project and penetrate infra red rays into the coat of hardened paint to bring about the softening and separation specified, such rays being produced by covering the heated surface of the device with a suitable ray transmitting coating of such character that it is capable of withstanding the relatively high degree of heat to which it is subjected.

A further aim or object of my invention is to supply a heater which will do the intended work and the heating means of which may be brought into comparatively close relation to the

2
painted surface without fire or electrical hazard and without danger of injuring the heater itself and without likelihood of causing the appliance to become gummed up or soiled or mechanically or electrically damaged by the heated plastic paint.

Another purpose of the invention is to supply a heater which will function in the specified manner and in which the heating element will be adequately protected and shielded against oxidation or deterioration and against mechanical injury.

To the accomplishment of these and other desirable objects, I have invented the present preferred embodiment of the invention, illustrated in the accompanying drawing and described in detail below, like reference numerals being employed, for the sake of simplicity, to designate the same structural elements in all of the views of the drawing.

In the drawing:

Figure 1 is a front elevation of my device.

Figure 2 is a side elevation, partly in section, of my device.

Figure 3 is a section on line 3—3 of Fig. 2.

Referring to the drawing, it will be observed that my device includes a substantially square casing 4, the face 5 of which is open, the said case forming a heat reflecting unit. Within the case 4 is positioned a tray member 6, upon the outer face of which is a sheet of insulating material 7 against which is supported a block 8, composed of suitable heat resisting material through which radiant heat is adapted to be projected, such as aluminum oxide fire clay, carbon, or other appropriate cement. In the rear face the block 8 is provided with connected grooves or channels 9 which accommodate a zig-zag coiled, electric heating element 10 which is shielded from the work by the wall 11. Perforation 12, through the wall 11 exposing limited portions of the heating element 10 may be provided to afford circulation as an aid to convection heating. Preferably the terminals 13 and 14 of the heating element are connected to the wires of cable 15 which passes through the handle 16 which is angularly attached to the case 4 by the tubular member 17. As shown in Fig. 3, the case 4 is preferably equipped with a cover 18 which is adapted to be removably secured over the open face 5 by means of a suitable latch means 19, the said cover being provided with a flange 19 as indicated.

From the above it will be seen that I provide a useful and novel appliance for the purposes

specified in which the heating element is shielded and protected from the work of paint softening. It will be seen that the device is simple, inexpensive and of rugged construction. The tray 6 may be held in position within the case 4 by spot-welding or other suitable means and the block assembly may be removably held in place by means such as the screw 20.

When a layer of paint has been softened by the means described, it can readily be scraped off by any suitable implement.

The invention is not limited to the exact details of construction herein presented and modifications may be resorted to without departing from the spirit of the invention as established by the scope of the claim.

I claim:

An electric paint softener including a hollow case member having one side open to form an open face and having the opposite side closed, a refractory block element exposing a substantially flat plane face to the open face of the case member, the block element having an open channel formed in the rear or inner opposite face of said block element facing in the opposite direction from its flat face, an imperforate tray member secured within the case member forming a

continuous floor remote from the open face thereof to which the block element is secured, heat insulating material disposed between the floor and the block element, the latter element having the channel therein exclusively facing the insulating material, and an electric heating element freely mounted within the channel in said block element and concealed within the latter and facing the rear or closed side of said case member as well as the floor and insulating material between said floor and block element.
